UNITED STATES PATENT OFFICE.

WILLIAM BREWSTER, OF NEW YORK, N. Y., ASSIGNOR TO BREWSTER & CO., A CORPORATION OF NEW YORK.

DESIGN FOR A RADIATOR-CASING FOR MOTOR-CARS.

49,878.

Specification for Design.

Patented Nov. 14, 1916.

Application filed August 22, 1916. Serial No. 116,396. Term of patent 14 years.

To all whom it may concern:

Be it known that I, WILLIAM BREWSTER, a citizen of the United States, residing in the borough of Manhattan, city, county, and State of New York, have invented a new, original, and ornamental Design for a Radiator-Casing for Motor-Cars, of which the following is a specification, reference being had to the accompanying drawing, forming part thereof.

The figure is a front elevation of a radiator showing my new elliptical design for the front end of the radiator.

I claim:

The ornamental design for a radiator-casing for motor cars, substantially as shown.

WILLIAM BREWSTER.
